UNITED STATES PATENT OFFICE.

JOHN H. WIGGINS, OF BARTLESVILLE, OKLAHOMA.

FLOATING DECK OR ROOF FOR LIQUID STORAGE TANKS.

Application filed November 9, 1922. Serial No. 399,304.

To all whom it may concern:

Be it known that I, JOHN H. WIGGINS, a citizen of the United States, residing at Bartlesville, Oklahoma, have invented a certain 5 new and useful Improvement in Floating Decks or Roofs for Liquid Storage Tanks, of which the following is a full, clear, and exact description, such as will enable others skilled in the art to which it appertains to 10 make and use the same.

This invention relates to liquid storage tanks of the type that comprise a deck or roof which normally floats upon the liquid in the tank.

15 One object of my present invention is to provide a floating deck or roof for liquid storage tanks that is equipped with a relatively deep truss which is combined with the deck in such a manner that the truss members do not project upwardly above the top side of the deck to such a height that they will interfere with any transverse tie members or braces that extend horizontally across the tank and do not project downwardly from the underside of the deck to such an extent as to make it impracticable to use an inside truss for reinforcing and strengthening the deck.

20 Another object is to provide a trussed floating deck or roof of simple design and inexpensive construction in which the truss members will always be taut.

25 And still another object is to provide a means for draining the top surface of a floating deck or roof which rests upon oil or other liquid that is of less specific gravity than water, that overcomes the necessity of using a jointed drain pipe to provide for the rise and fall of the deck, due to variations 30 in the level of the liquid in the tank. Other objects and desirable features of my invention will be hereinafter pointed out.

35 To this end I have devised a floating deck or roof for liquid storage tanks that is equipped with a deep truss which is combined with the deck in such a manner that some of the truss members are arranged above the deck and the remainder of the truss members are arranged on the under- 40 side of the deck. The truss preferably comprises a vertical strut at the center of the deck composed of a member arranged above the deck and a member arranged on the under- 45 side of the deck, a plurality of radially-disposed compression members on the under- 50 side of the deck arranged approximately

parallel with the deck and connected at their inner ends to the center strut and at their outer ends to vertical struts whose upper ends are rigidly connected to the deck, and 55 radially-disposed tension members arranged at their inner ends to the upper end of the center strut and at their outer ends to the outer ends of the compression members on the underside of the deck, each of said tension members being composed of two parts, 60 one of which is secured to the deck and to the upper end of the center strut and the other being secured to the deck and to the outer end of the particular compression 65 member with which it co-operates. Means is provided for adjusting some of the members of the truss so as to insure that the co-operating elements of the truss will always be taut, and while various means may be 70 used for this purpose without departing from the spirit of my invention, I prefer to use a means that can also be used for deflecting the central portion of the deck so as to increase the buoyancy of the deck and 75 also produce a depressed portion in the top side of the center of the deck into which water on the surface of the deck will drain.

80 As previously stated, one object of my present invention is to eliminate the jointed drain pipe that is generally used for carrying off water from the top side of a floating deck or roof for oil storage tanks. I accomplish this desirable result by using one or 85 more inverted siphons, each of which comprises a draining device that leads from the top side of the deck and which terminates inside of the tank in such a way that while it permits water to drain from the top side of the deck into the bottom of the tank at 90 a point below the oil in the tank, it will not permit the oil in the tank to escape upwardly through said draining device, due to the fact that the oil in the tank is of 95 less specific gravity than the water in said 100 draining device. The draining device just referred to can be constructed in various ways, so long as it is of such design that it will virtually form a U-shaped tube filled with water and having a long leg communicating at its upper end with the surface to be drained and a short leg which terminates inside of the tank. Normally, the water stands in the long leg of said tube at such a 105 level that it balances the liquid in the tank, thereby effectively cutting off the escape of 110 the liquid in the tank through said tube.

Whenever additional water enters the long leg of said tube from the surface to be drained, namely, the top side of the deck of the tank, the siphon becomes unbalanced and 5 some of the water in said tube escapes therefrom into the lower portion of the tank, wherein the water collects at a point below the body of liquid in the tank. At intervals the water in the bottom portion of the 10 tank is allowed to escape by opening a drain cock or valve in the lower portion of the tank. In the form of my invention herein illustrated the inverted siphon or substantially U-shaped draining device above referred to is formed by a vertically-disposed pipe arranged so that water can flow into same from the top side of the deck of the tank and a depending extension on the bottom of the tank that receives the lower end 15 portion of said tube, said extension being long enough to provide for the rise and fall of the deck, due to variations in the level of the liquid in the tank, and the upper end of said extension being in direct communication with the tank so that the drain water which enters said extension from the lower end of the drain pipe can flow upwardly into the tank and collect therein at a point below the body of oil or other liquid in the 20 tank. I do not wish it to be understood, however, that my invention is limited to a draining device formed by a depending drain pipe on the floating deck of the tank and a depending extension on the bottom of 25 the tank which receives the lower end portion of said drain pipe, as the same result can be accomplished in various other ways without departing from the spirit of my invention. Furthermore, while I have herein 30 illustrated my improved draining means used in connection with a trussed deck or roof, I wish it to be understood that it is not limited to use with such a deck, but is capable of use with any type or kind of 35 deck that floats upon a body of liquid of less specific gravity than water.

Figure 1 of the drawings is a diagrammatic view on a reduced scale, illustrating how the radially-disposed tension members 50 and the compression members of the truss of the deck are arranged; and

Figure 2 is a vertical transverse sectional view of a portion of an oil storage tank equipped with a floating deck embodying my invention, said view being taken on approximately the line 2-2 of Figure 1.

Referring to Figure 2 of the drawings, A designates the cylindrical side wall of a tank that is used for storing oil or other liquid of less specific gravity than water, B designates the bottom of the tank and C designates the central body portion of a deck or roof that normally floats upon the liquid in said tank. The central body portion C 65 of the deck is preferably formed from thin

metal plates secured together in such a way as to produce a single limber, solid sheet that covers the major portion of the body of liquid in the tank, and the space between the side wall of the tank and the peripheral 70 edge of the central body portion C of the deck is closed by a means that is capable of expanding and contracting sufficiently to compensate for variations in the relative position and dimensions of the deck and the side wall of the tank, which means may be of similar construction to the variable peripheral portion of the deck described in either of my pending applications for patents Serial No. 540,847, filed March 3, 1922 75 and Serial No. 599,903, filed November 9, 1922. One feature of my present invention consists of a truss of novel construction for reinforcing and strengthening a deck or roof that floats upon a body of liquid in a storage 80 tank. Said truss comprises a vertically-disposed strut arranged at the center of the deck C and composed of a member D arranged above the deck with its lower end bearing against the deck and a member D' 85 arranged below the deck with its upper end rigidly connected to the deck, a plurality of radially-disposed compression members E on the underside of the deck arranged substantially parallel to same with their inner 90 ends joined to the center strut and their outer ends joined to vertically-disposed struts F whose upper ends are rigidly connected to the deck, and a plurality of radially-disposed tension members connected 95 at their inner ends to the upper end of the center strut and connected at their outer ends to the outer end portions of the compression members E, each of said tension members comprising a part G arranged 100 above the deck and a part G' arranged below the deck, as shown in Figure 2, both of which parts are rigidly connected to the deck. Means is provided for adjusting certain members of the truss so as to insure 105 that the truss members will always remain taut, and thus be in a condition to immediately counteract any unequal load that is applied to the deck, and while various means may be used for this purpose, I prefer to equip the part G' of each of the tension members with a turn-buckle 1 and secure the inner end of the part G of each tension member to a vertically-adjustable 110 connecting member 2 on the upper member D of the center strut that is arranged above the deck C, said member 2 being adapted to be moved upwardly by turning a nut 3 mounted on a screw-threaded portion 3a of the center strut at a point beneath the member 2. When the nut 3 is turned in a direction to move the connecting member 2 upwardly the parts G of the radially-disposed 115 tension members will be placed under greater tension and a downward force will 120 125 130

be exerted on the deck C sufficiently to deflect the central portion of the deck, as shown in Figure 2. This deflection of the central portion of the deck not only imparts greater buoyancy to the deck, but it also causes a depression to be formed in the top side of the deck at the center of same into which water on the top side of the deck naturally drains. The operation of tightening the turn-buckles 1 takes up the slack in the members of the truss that are arranged on the underside of the deck C, the compression members E held rigid by vertically-disposed, depending braces 4 on the underside of the deck, and the inner ends of said compression members being rigidly connected to the bottom member D' of the center strut by means of a hollow connecting member H from which said compression members E branch radially. So far as trussing of the deck is concerned, it is immaterial whether the compression members and the struts are formed from solid rods or pieces of tubing, but in order to simplify the construction of the deck and enable some of the truss members to be used as conduits for carrying off rain that falls on the deck, I prefer to construct the compression members E from pipes and construct the struts F and the lower member D' of the center strut from pieces of pipe, the hollow connecting member H that is used to join the compression members E to the center strut consisting of a drain manifold that connects all of the radially-disposed drain pipes E with a vertically-disposed drain pipe D' arranged at the center of the deck.

This method of constructing the deck makes it practicable to equip the deck with a relatively deep truss, due to the fact that some of the truss members are arranged above the deck and some of the truss members are arranged below the deck, thereby preventing the truss members above the deck from interfering with any transverse tie members that may be used to brace the side wall of the tank and those beneath the deck from seriously interfering with the downward movement of the deck during the operation of drawing the liquid out of the tank. Another desirable feature of such a deck is that it can be manufactured at a low cost, due to the fact that standard pipe and pipe fittings may be used to form most of the members of the truss, the vertical struts consisting of pieces of pipe that are screwed into collars 5 that are welded to the deck or connected to same in any other suitable way. The depressed central portion of the deck imparts great buoyancy to the part of the deck from which the drain manifold H is suspended, and as means is provided for taking up the slack in the radially-disposed tension members, the various elements of the truss can be kept taut

enough to insure the truss immediately counteracting any uneven loads that are applied to the deck.

As previously stated, one feature of my present invention consists of a drainage means for a floating tank deck or roof which is constructed in such a way that it is not necessary to use a jointed or flexible drain pipe to provide for the rise and fall of the deck, due to variations in the level of the liquid in the tank. This improved drainage means may be described briefly as consisting of one or more inverted siphons, each of which is composed of a draining device communicating at its upper end with the top side of the deck or with a drain pipe that leads from the top side of the deck and having its lower end terminating inside of the tank in such a way that water which falls onto the deck will be conducted by said draining device down into the lower portion of the tank at a point below the body of liquid in the tank. In the form of my invention herein illustrated the draining device just referred to is formed by a vertically-disposed drain pipe I that forms a continuation of one of the vertical struts F of the truss and which projects downwardly into a depending extension I' on the bottom B of the tank, said extension I' being long enough to provide for the rise and fall of the deck C, due to variations in the level of the liquid in the tank. Rain that falls on the top surface of the deck C will be conducted by the tubular truss members D', E and F to the drain pipe I down through which it flows into the depending extension I' on the bottom of the tank, the drain water passing upwardly through the extension I', as indicated by the arrows in Figure 2, and finally collecting in the bottom of the tank at a point below the body of liquid in the tank on which the deck C floats. Normally, the extension I' on the bottom of the tank contains sufficient drain water to seal the lower end of the drain pipe I, and said drain pipe, as well as the members D', E and F of the truss, are filled with drain water, the normal level of the drain water in the members D' and F of the truss being indicated by the reference character α in Figure 2. Notwithstanding the fact that the level of the liquid in the tank is higher than the level of the liquid in the pipes D' and F that lead from the top surface of the deck C, it is impossible for the liquid in the tank to escape upwardly through the drain pipe I and the pipes D', E and F that communicate with same, due to the fact that the liquid in the tank, which I will assume is oil or a similar substance, is of less specific gravity than the drain water in the pipe I and the pipes D', E and F with which it communicates. When rain falls on the deck C it will eventually find its way into the drain pipes D' and F, thereby

increasing the weight of the column of drain water that opposes the column of oil in the tank, and consequently, causing the siphon to become unbalanced, whereupon more water 5 will flow upwardly through the extension I' on the bottom of the tank and collect in the tank beneath the body of oil therein. At frequent intervals excess drain water is removed from the bottom of the tank through 10 a draw-off pipe 6 that is provided with a valve 7. From the foregoing it will be seen that the drain pipe I and the extension I' on the bottom of the tank into which said drain pipe extends co-operate with each 15 other to form practically a U-shaped tube filled with drain water and arranged with the upper end of its short leg communicating with the body of oil in the tank and the upper end of its long leg communicating 20 with the top surface of the deck, the greater specific gravity of the column of water in said tube causing said column of water to act like a check valve to permit drain water to enter the bottom of the tank and to cut 25 off the escape of the contents of the tank through said U-tube. In addition to forming a very efficient means for draining the top surface of the deck C, the drain pipe I co-operates with the depending extension I' on 30 the bottom of the tank to prevent the floating deck C of the tank from rotating or turning relatively to the side wall A of the tank. It is, of course, immaterial to what part of the 35 draining system the pipe I is connected, so long as the upper end of said pipe communicates with the surface to be drained, or with a system of drain pipes into which water flows from the surface to be drained. Moreover, while I have herein illustrated the pipe 40 I as projecting downwardly into the extension I' on the bottom of the tank, it will, of course, be obvious that the same result could be accomplished by using a drain pipe leading from the draining system and having its 45 lower end bent upwardly so as to produce a substantially U-shaped tube composed of a long leg and a short leg.

Having thus described my invention, what I claim as new and desire to secure 50 by Letters Patent is:

1. A floating deck for liquid storage tanks provided with a relatively deep truss combined with the deck in such a manner that some of the truss members are arranged 55 above the deck and some are arranged below the deck.

2. A floating deck for liquid storage tanks provided with a truss comprising members arranged above and below the deck, and 60 means for adjusting said truss members so as to keep them taut.

3. A floating deck for liquid storage tanks provided with a truss comprising members arranged above and below the deck, and 65 means for exerting pressure on the deck 70

in such a way as to deflect the central portion of same and thus increase the buoyancy of the deck.

4. A floating deck for liquid storage tanks provided with a truss comprising compression members and struts arranged on the underside of the deck, and inclined tension members connected at one end to said compression members and at their opposite 75 ends to a strut that projects upwardly from the top side of the deck.

5. A floating deck for liquid storage tanks provided with a center truss that projects upwardly and downwardly from the deck, compression members on the underside of 80 the deck that branch radially from said center strut, and tension members connected at their inner ends to the upper end of said center strut and at their outer ends to said compression members.

6. A floating deck for liquid storage tanks, comprising a center strut that projects upwardly and downwardly from the deck, compression members on the underside of 85 the deck that branch radially from said center strut, vertically-disposed struts on the underside of the deck to which the outer ends of said compression members are connected, and inclined tension members connected at their outer ends to said compression members and at their inner ends to the upper end of said center strut.

7. A floating deck for liquid storage tanks, comprising vertically-disposed struts arranged on the underside of the deck at the 100 center and at the outer edge of same, radially-disposed compression members on the underside of the deck connected to said struts, a center strut projecting upwardly from the top side of the deck, and inclined tension members leading from the outer ends of said compression members to the upwardly-projecting strut and connected to the deck at points intermediate the ends of 105 said tension members.

8. A floating deck for liquid storage tanks, comprising a strut member projecting upwardly from the top side of the deck at the center of same, and inclined tension members connected to the upper end of 110 said strut and to the deck.

9. A floating deck for liquid storage tanks, comprising a strut member projecting upwardly from the top side of the deck at the center of same, inclined tension members connected to the upper end of said strut and to the deck, and means for varying the point of connection between said tension members and strut so as to exert pressure on the deck in a direction tending 125 to deflect the central portion of same.

10. A floating deck for liquid storage tanks, comprising a vertically-disposed strut member projecting upwardly from the top side of the center of the deck and hav- 130

- ing no direct connection with the deck, a vertically-adjustable part on said strut member, and inclined tension members connected to said part and to the deck.
- 5 11. A floating deck for liquid storage tanks, provided with a truss comprising members arranged on the underside of the deck and members arranged on the upper side of the deck, means for adjusting the 10 truss members on the underside of the deck to take up the slack in same, and an independent means for adjusting the truss members on the upper side of the deck.
12. A floating deck for liquid storage 15 tanks provided with a relatively deep truss comprising members arranged above and below the deck, some of the truss members on the underside of the deck being formed from pieces of pipe or tubing and arranged 20 in such a way that they can be used to carry off drain water from the top side of the deck.
13. A floating deck for liquid storage 25 tanks provided at its center with a depending drain pipe, a plurality of radially-disposed conduits that branch from said drain pipe, and an outlet leading from one of said conduits to the bottom of the tank.
14. A tank for storing oil or other liquid 30 of less specific gravity than water, comprising a floating deck, and means for draining the top surface of said deck and conducting the drain water down into the bottom of the tank below the body of oil in the tank.
- 35 15. A tank for storing oil or other liquid of less specific gravity than water, comprising a floating deck, means for draining the top surface of said deck and conducting the drain water down into the bottom of the 40 tank below the body of oil in the tank, and means for enabling the drain water to be removed from the lower portion of said tank.
- 45 16. A tank for storing oil or other liquid of less specific gravity than water provided with a deck that floats upon the body of oil in the tank, and an inverted siphon for conducting water from the top side of said deck
- into the lower portion of the tank below the body of oil therein.
- 50 17. A tank for storing oil or other liquid of less specific gravity than water provided with a floating deck, and a substantially U-shaped draining means having the upper end of one of its legs communicating with the top side of said deck and the upper end of its other leg communicating with the interior of the tank.
- 55 18. A tank for storing oil or other liquid of less specific gravity than water provided with a floating deck, and means for draining the top surface of said deck comprising a drain pipe projecting downwardly from the deck, and an extension on the bottom of the tank which receives said drain pipe.
- 60 19. A tank for storing oil or other liquid of less specific gravity than water provided with a floating deck, a vertically-disposed drain pipe projecting downwardly from the deck, and an extension projecting downwardly from the bottom of the tank that is adapted to receive said drain pipe.
- 65 20. A tank for storing oil or other liquid of less specific gravity than water provided with a floating deck, and a drain pipe for 70 conducting water from the surface of the deck into the lower portion of the tank, arranged so that it will normally be filled by a column of drain water that acts as a check valve to admit drain water to the lower portion of the tank but which prevents the escape of either oil or drain water from the tank.
- 75 21. A tank for storing oil or other liquid of less specific gravity than water provided with a floating deck, a drainage means on the underside of the deck adapted to receive water that falls onto the deck, a drain pipe projecting downwardly from said means and a vertically-disposed extension on the bottom of the tank that receives said drain pipe and which is of such proportion relative to said drain pipe that the lower end of said drain pipe is always located at a point 80 below the bottom of the tank.

JOHN H. WIGGINS.
